ATTOR

UNITED STATES PATENT OFFICE.

JAMES BEESLEY, OF BROOKLYN, NEW YORK.

DESIGN FOR A CHANDELIER.

SPECIFICATION forming part of Design No. 27,706, dated September 28, 1897.

Application filed July 17, 1897. Serial No. 644,990. Term of patent 7 years.

To all whom it may concern:

Be it known that I, JAMES BEESLEY, of Brooklyn, in the county of Kings and State of New York, have invented and produced a new and original Design for a Chandelier, of which the following is a full, clear, and exact description.

Reference is to be had to the accompanying drawing, forming a part of this specification, in which the figure is a perspective view of a chandelier embodying my design.

The body A of the chandelier has the semblance of a drinking-horn and is apparently transparent or translucent, disclosing the outline of an electric-lamp bulb D. On the body appears a band B, displaying borders, the one crown-like and the other leaf-like, between which appear a series of scroll-like figures. On the tip C of the body appear crown-like bands and scrolls, the extremity of the

tip curving into a shell-like figure. The body appears suspended by rods E and F, ornamented at intervals by foliate figures, the upper extremities of the rods meeting in a globular figure. The lower ends of the rods F terminate in knob-like figures at the band B, while the lower end of the rod E joins a curved figure emanating from the tip C.

The leading feature of my design is the chandelier in the semblance of a drinking-horn and having an ornamental band and tip and suspending-rods attached thereto.

I claim—

The design for a chandelier as herein shown and described.

JAMES BEESLEY.
